UNITED STATES PATENT OFFICE.

LOENDER C. EMERSON, OF NORTH GRAFTON, MASSACHUSETTS, ASSIGNOR
OF ONE-HALF TO CHARLES H. NELSON, OF SAME PLACE.

BUTTON-SETTING MACHINE.

SPECIFICATION forming part of Letters Patent No. 368,141, dated August 9, 1887.

Application filed May 13, 1887. Serial No. 238,107. (No model.)

To all whom it may concern:

Be it known that I, LOENDER C. EMERSON, a citizen of the United States, residing at North Grafton, in the county of Worcester and State 5 of Massachusetts, have invented certain new and useful Improvements in Button-Feeding Mechanisms for Button-Setting Machines, of which the following is a specification, reference being had therein to the accompanying drawings.

My invention relates to a button-feeding mechanism for button-setting machines, the said invention being more especially adapted for operation in connection with the form of 15 button-setting machine shown by United States Patent No. 341,053 to F. H. Richards.

In my invention I use a rotary button-carrying head or carrier, which takes the place of the "die-holder" in the patent above referred 20 to. This rotary head or carrier is provided with a series of retaining-springs for the buttons and with a series of setting dies or anvils, against which the fasteners are forced by the driver to bend them in proper shape to hold the 25 buttons on the shoes or fabrics to which they are to be attached. In connection with the rotary button-carrier I employ a movable chute or roadway, which conducts the buttons from the box or receptacle in which they are contained to 30 the said carrier, and the latter is intermittently rotated by a pawl-and-ratchet mechanism connected by a rod with the treadle by which the driver is operated. The movable button-conducting roadway or chute is reciprocated by 35 a lever operated by the pawl-carrier, which actuates the rotary button-carrier, and by a retracting-spring. The said chute is moved toward the button-carrier, so that it may force a button into the same when the treadle is op- 40 erated; but before the chute begins its retreat from the carrier the latter commences its rotation, and thus removes the button from the spring-holding fingers at the lower end of the chute before the latter moves away from the 45 carrier. A partial rotation of the carrier brings the button into position to be set at the next blow of the driver, so that while one button is being set another is being placed in the carrier preparatory to the setting operation.

50 In the drawings, Figure 1 is a front view of a

button-setting machine with my invention applied thereto. Fig. 2 is a side view of the same. Fig. 3 is a detail plan view showing the button-chute in section in the position it occupies when placing a button in the carrier. 55 Fig. 4 is a partial section on line 4-4, Fig. 2, and with parts in the same position as in Fig. 3; and Fig. 5 is a detail view of the button-chute.

A denotes the frame of the machine, the said 60 frame being in practice supported by an iron column, which incloses the treadle-rod for operating the driver.

B is a vertical post in which the driver (not 65 shown) reciprocates, and C is the magazine to contain the fasteners, all as in the patent above referred to.

D is a support or bracket, which is screwed to the frame A, the said bracket having a dovetailed recess or guideway, d, for the reception 70 of a dovetailed projection on a slide, E, to which is attached the button box or receptacle F. The button roadway or chute G is attached to the base-plate f of the button-box F, the said chute having a quarter turn or twist, 75 as shown in Fig. 5, to bring the buttons from their position with their heads down, in which they enter the chute, to a position in which the shanks will be horizontal, as in Fig. 3. The said chute is provided at its lower end with re- 80 taining-springs g and g', to prevent the buttons from falling out and to hold them when being presented to the rotary button-carrier. The buttons in the box F are forced into the chute G by an ordinary agitating-brush operated in 85 any suitable manner.

I is the rotary button-carrying head or carrier, having a shaft, i, which has a bearing in the top of the frame A, the said shaft having a ratchet-wheel, H, engaged by a spring-pressed 90 pawl, h, pivoted to a lever, J, and the latter is pivoted on the shaft i and is provided with a roller-stud, h'. A rod, J', connects the lever J with the treadle by which the driver is op- 95 erated, and a detent-spring, h², prevents the backward movement of the wheel H. The bracket D has a depending arm or hanger, d', to which is pivoted a bell-crank lever, K, the lower arm of which is in position to be acted on by the roller-stud h' on the pawl-carrying 100

lever J, the upper or vertical arm of the said lever being connected by the link L to the slide E.

N is a retracting-spring attached to the lever 5 K and to the support or bracket D.

The rotary button-carrying head or carrier I is provided with a series of button-holding springs, i' , projecting beyond the periphery of a disk, i^2 , on the face of the said carrier, the 10 said disk being of lesser diameter than the said head, so that there will be a proper space between the ends of the said springs and the rim of the said head to receive the heads of the buttons. Opposite each of the springs i' is a setting die or anvil, M, constructed, as shown in the patent referred to, with a recess of proper form to bend over or clinch the fasteners.

The operation of my device is as follows: When the treadle (not shown) is operated, the 20 downward movement of the rod J' depresses the outer end of the pawl-carrying lever J, and the roller-stud h' thereon engages the inclined outer end, k , of the horizontal arm of the lever K, thus turning said lever on its fulcrum and 25 causing the slide E, connected by the link L to the vertical arm of the said lever, to move to the left, Fig. 1, and thus the lower end of the chute G will move into engagement with the rotary button-carrier I and place a button in 30 the said carrier behind one of the holding-springs i' . When the treadle is released, a suitable retracting-spring (not shown) in the supporting-column of the machine forces the rod J' upward, causing the pawl h to engage 35 a tooth of the ratchet-wheel H, and thus give a quarter-turn to the carrier I, bringing the button above the post B into position to be set. During the first part of the operating 40 movement of the pawl-carrier (as the rod J' moves upward, as just described) the roller-stud h' will traverse the curved portion k' of the horizontal arm of the lever K before it rides down the inclined end k of the said arm, and thus the said lever will remain at rest, with 45 the button-chute still in its forward position, until a partial rotation of the carrier I has been effected and the button has been carried downward out of the lower end of the chute, the springs g and g' yielding to release the lower 50 button from the chute, but immediately retracting to prevent other buttons from escaping. As the roller-stud h' rides down the inclined end k of the lever K, the retracting-spring N, acting through the lever K, link L, slide E,

and the button-box, (to the base of which latter the button-chute is attached,) returns the chute to its original position. The next downward movement of the rod J' sets the button now brought into setting position above the post B and causes the forward movement of 60 the chute G to place another button in the rotary carrier I, and thus the button feeding and setting operations will be repeated as rapidly as the treadle can be worked.

I do not wish to be understood as limiting 65 my invention to the precise details of construction herein shown and described, as such details may be varied within the limits of mechanical skill without departing from the spirit of my invention. For example, the rotary head or carrier I, instead of having four button-holding springs and four setting-dies, as herein shown, (and being thus adapted to perform a quarter-revolution at each operation of the treadle,) might have a greater or 70 less number of these springs and dies, and thus be adapted to be rotated through a greater or less portion of a circle at each operation of the treadle.

I claim—

1. In a button-feeding mechanism, the combination herein described, with a rotary button-carrier provided with button-holding springs and setting dies or anvils, of a reciprocating button-chute adapted to approach the said carrier to place the buttons therein, substantially as set forth.

2. In a button-feeding machine, the combination, with the rotary button-carrier I, having the holding-springs i' and the setting dies or anvils M, of the ratchet-wheel H, the pawl-carrier J, having the stud h' , the spring-pressed pawl h , the bell-crank lever K, and the movable button-chute with which the said lever is operatively connected, substantially as set 95 forth.

3. The rotary head or button-carrier I, having on its front face the disk i^2 , of less diameter than the said head, combined with the button-holding springs i' , extending beyond the periphery of the said disk, substantially as set forth.

In testimony whereof I affix my signature in presence of two witnesses.

LOENDER C. EMERSON.
